UNITED STATES PATENT OFFICE.

WILLIAM H. LUCAS, OF NEWARK, OHIO.

VAULT-MOLD.

No. 806,686.

Specification of Letters Patent.

Patented Dec. 5, 1905.

Application filed May 26, 1905. Serial No. 262,267.

To all whom it may concern.

Be it known that I, WILLIAM H. LUCAS, a citizen of the United States, residing at Newark, in the county of Licking and State of Ohio, have invented certain new and useful Improvements in Vault-Molds; and I do declare the following to be a full, clear, and exact description of the invention, such as will enable others skilled in the art to which it appertains to make and use the same.

My invention relates to improvements in molds for forming vaults of concrete or other plastic material; and it consists in the novel construction, combination, and arrangement of parts hereinafter shown and described.

The object of the invention is to provide a simple, inexpensive, durable, and efficient sectional mold of this character which may be quickly set up for use and knocked down to facilitate its removal from the molded structure.

The above and other objects, which will appear as the nature of my invention is better understood, are accomplished by means of the construction illustrated in the accompanying drawings, in which—

Figure 1 is a vertical longitudinal sectional view through a vault-mold constructed in accordance with my invention. Fig. 2 is a horizontal sectional view through the same, taken 30 on the line 2 2 in Fig. 1. Fig. 3 is a detail sectional view, on an enlarged scale, taken on the line 3 3 in Fig. 1; and Fig. 4 is a detail sectional view taken on the line 4 4 in Fig. 1.

The embodiment of the invention illustrated 35 in the drawings is adapted for forming vaults and foundations of superstructures and comprises a plurality of sections 2, which are detachably connected. As shown, the mold is of rectangular form and is composed of ten 40 sections, three being on each side and two at each end. Each of the sections comprises a body portion 3 of suitable width and length and preferably formed of sheet metal. Along one of the longitudinal edges of each section 45 is formed an offset portion 4, which is adapted to overlap the adjacent edge of the contiguous section. These offset portions 4 are adapted to abut against the ends of metallic battens or cleats 5, which are riveted or otherwise secured transversely across the inner 50 faces of the bodies or plates 3 at suitable intervals. The portions 4 are held in engagement with the battens 5, and the sections of the mold are held rigidly in alinement with each other by fastening devices 6, which are 55 preferably in the form of hooks, pivoted at

one of their ends, as shown at 7, upon the battens of one section and adapted to engage headed studs or pins 8 upon the battens of the adjacent or contiguous section. These 60 hooks 6 are preferably formed of flat metal and have notches or recesses 9 in their free ends to engage the pins or studs 8. The outermost sections 2^a of each side of the mold are preferably formed at one of their sides with 65 right-angularly-bent portions or flanges 10, which are adapted to engage the outermost sections of the ends of the mold, as clearly shown in Fig. 5 of the drawings. The sections at the corners of the mold are held together by hooks 11, which are pivoted in eyes 12 and are adapted to engage headed studs 13.

In using the mold a hole is made in the earth larger than the mold, and the sections are then set up on end in the hole and locked together. 75 The space between the sides of the hole and the outer faces of the mold is then filled in with concrete or other plastic material from which the vault or other structure is to be formed, and after this material has become 80 set or hardened the mold may be readily removed by detaching its sections from each other. It will be seen that owing to the manner in which the mold-sections are secured together a rigid mold is produced which may be 85 quickly set up or knocked down, as desired.

Various changes in the form, proportion, and the minor details of construction may be resorted to without departing from the principle or sacrificing any of the advantages of 90 this invention.

Having thus described my invention, what I claim as new, and desire to secure by Letters Patent, is—

The herein-described mold comprising the 95 plurality of sections each having one edge offset laterally to overlap the opposing edge of the next adjacent section, the battens disposed transversely on the inner sides of and secured to the several sections, and the hooks each pivoted on the inner side of a batten on one section, extending over the overlapped edges of said section and the next adjacent section and detachably secured to and bearing against the batten of said next adjacent section. 100 105

In testimony whereof I have hereunto set my hand in presence of two subscribing witnesses.

WILLIAM H. LUCAS.
